UNITED STATES PATENT OFFICE.

JOHN A. MOORE, OF LOUISVILLE, KENTUCKY, ASSIGNOR TO THE MENGE COMPANY,
OF LOUISVILLE, KENTUCKY, A CORPORATION OF NEW JERSEY.

MACHINE FOR SEALING BOXES OR CARTONS.

1,379,276.

Specification of Letters Patent.

Patented May 24, 1921.

Application filed June 14, 1920. Serial No. 388,831.

To all whom it may concern:

Be it known that I, JOHN A. MOORE, a citizen of the United States, residing at Louisville, in the county of Jefferson and 5 State of Kentucky, have invented certain new and useful Improvements in Machines for Sealing Boxes or Cartons, of which the following is a specification.

This invention pertains to an improved 10 machine for closing and sealing boxes or cartons, and has for its main object the production of a machine wherein filled boxes or cartons will have their closure flaps automatically turned in and sealed.

15 The invention is illustrated in the accompanying drawings, wherein,—

Figure 1 is a top plan view of the machine;

Fig. 2 a vertical longitudinal sectional 20 view;

Fig. 3 a transverse sectional view taken on the line III—III of Fig. 2;

Fig. 4 a similar view taken on the line 25 IV—IV of Fig. 2 and showing the flaps being brought to their final closed position;

Fig. 5 a detailed sectional elevation showing a portion of the paste operating mechanism;

Fig. 6 a horizontal sectional view;

30 Fig. 7 a perspective view showing one of the cartons or boxes with the means employed for outwardly turning the outermost flaps both at the upper and lower end of the box or carton prior to their entering into 35 operative relation with the paste applying rollers;

Fig. 8 a similar view showing the flaps being brought to their final closed position;

Fig. 9 a transverse vertical sectional view 40 taken on the line IX—IX of Fig. 2 with the box in place, and

Fig. 10 an enlarged side elevation showing the means for driving the paste applying elements.

45 The machine is designed more particularly to apply paste to two of the flaps both at the upper and lower ends thereof, and to turn such flaps inwardly upon the other flaps of the box and to cause the same to 50 adhere to such previously inturned flaps. The box or carton is best shown in Fig. 7 wherein 1 denotes the body of the box, 2 and 3 the inturned flaps at the upper ends thereof, 4 and 5 the side or overlying flaps, 55 the flaps at the lower end of the box being

similarly lettered and having added thereto the exponent *a*. The frame of the machine may be said to be composed of an upper element 6 and a lower element 7 which lie horizontally parallel to each other and 60 are connected by suitable frame elements as the vertically disposed columns 8 and 9 which in turn are connected by cross braces 10 and 11. Located at a point beyond the frame members 6 and 7 is a receiving chamber 65 comprising upper and lower walls 12 and 13 respectively, connected together by cross pieces 14 and 15 and vertical elements 16 and 17. The boxes are introduced by hand on to the base member 7 with the 70 innermost flap, both at the top and bottom, turned inwardly, as best shown in Fig. 2, and the boxes will move through the machine or runway formed by the members 6 and 7, past the initial flap engaging mechanism or means which turns the outermost flaps outwardly into the horizontal where they are brought into alinement with the paste applying rollers, thence past said rollers and into working relation with the means 75 employed for inturning said pasted flaps upon the previously infolded flaps, thence into the receiving chamber where said in-turned flaps are held in their closed position until they become sufficiently dry to 80 adhere to the inner flaps. Or the boxes thus closed may be removed from the compression chamber and stacked or otherwise positioned where the flaps will be held closed 85 for the requisite length of time. 90

To advance the boxes or cartons through the runway, I preferably employ two endless chains 18 and 19, each chain being provided with a series of equally spaced lugs or fingers 20 (see Fig. 6) the outer ends of 95 which are preferably rearwardly curved to a slight extent so that they will not injure the box when they come into contact therewith. The inner stretches of the chains adjacent the runway run in grooved guide bars 21 and 22 (see more particularly Fig. 9) and pass about suitable driving sprockets and idlers best shown in Figs. 1 and 4). The chain 18 adjacent the discharge end of the machine passes about a sprocket 23 secured 100 upon the lower end of a vertical shaft 24 carrying at its upper end a bevel gear 25 which meshes with a similar gear 26 secured upon a driven shaft 27, said shaft receiving its power through a belt passing about a band 105 110

pulley 28. The chain 19 passes about a sprocket 29 secured to the lower end of a vertically disposed shaft 30 corresponding to shaft 24 and carrying at its upper end a 5 bevel gear 31 which meshes with a similar gear 32 secured to the shaft 27. Thus the shafts 24 and 30 are driven in unison and consequently the endless chains 18 and 19 likewise move in unison. The chain 18 10 passes about an idler 33 located substantially mid-length of the machine and about a second idler 34 located at the mouth or intake end of the machine, said idler 34 standing in line with sprocket 23 so that the inner run 15 of the chain as it passes through the groove in the guide bar 21 is straight. Chain 19 passes around an idler 35 similar to the idler 33, and about an idler sprocket 36 located at the intake end of the machine, thus holding 20 the inner stretch of said chain 19 straight and in parallelism with the inner run of the chain 18. The flaps which are to be pasted and turned downwardly or upwardly, as the case may be, are passed beneath the flap 25 turning mechanism which throws them upwardly into the horizontal as they pass into the machine. Such means, in the instant case, is shown both at the upper and lower portions as composed of two bars or members 30 each comprising an upstanding portion 37 and an inclined portion 38, the said inclined members inclining downwardly and diverging from each other, as best seen upon reference to Figs. 1 and 2, so that as the box 35 moves thereunder, the flaps 4 and 5 which contact the said elements 38 will be gradually turned outwardly and brought to the horizontal in line with the paste applying means. 40 Said paste applying means is automatic in its operation and is preferably constructed in the following manner: Located beneath the lower frame member 7 is a paste receptacle or trough 39 in which 45 rotates two rollers 40 and 41 carried upon a shaft 42 which at its outer end is provided with a gear 43. Said gear meshes with a similar gear 44 secured upon a shaft 45 which lies above and parallel to the shaft 42. 50 Said shaft 45 carries rolls 46 and 47 located directly above and in contact respectively with the rolls 40 and 41. Rolls 48 and 49 mounted upon stub axles 50 which extend inwardly from the vertically disposed members 8 and 9 of the frame, overlie the rolls 46 and 47 respectively, said rolls 48 and 49 being pressure rolls. The lowermost out-turned flaps of the box or carton, after having passed the spreading elements 38, lie 55 in a plane coincident with the bight between the rollers 46 and 48 and 47 and 49 and pass between the same, as best shown in Fig. 9, the paste being applied to the undermost faces of the then outturned flaps by the rollers 46 and 47. The shaft 45 has secured to 60 it a pulley 51 about which passes a belt 52, the belt being crossed over and passing about a pulley 53 secured to a shaft 54 mounted in suitable brackets 55 secured to the upper portion of the machine. Said shaft 54 also 70 has secured to it, approximately at its mid-length, (see Figs. 1 and 2) a pulley 56, about which passes a belt 57, said belt extending toward the discharge end of the machine and passing about a pulley 58 mounted upon the 75 drive shaft 27 heretofore referred to. Motion is thus imparted from the shaft 27 through belt 57, shaft 54 to pulley 53, thence through belt 52 and pulley 51 to the shaft 45 and the coöperating parts just described. 80 Shaft 27 also carries a second pulley 59 about which passes a belt 60 that extends toward the intake end of the machine, said belt passing over idlers 61 and 62 mounted upon a bracket 63 and about a pulley 64 secured upon a shaft 65. As will best be seen upon reference to Fig. 5, the belt 60 forms what may be termed a loop as it passes over the idler 61 about the pulley 64 and back to the idler 62, which loop becomes ineffective 90 to drive the shaft 65 when the parts are in the position shown in Fig. 2, that is to say, when the shaft 65 and its pulley 64 are elevated. The shaft 65 is mounted in the ends of a bail shaped frame, best shown in Figs. 95 1, 2 and 5, and denoted by 66. Said frame is fulcrumed upon a cross bar 67 secured in suitable brackets 68. The shaft 65 has secured to it paste applying rollers 69 and 70 which coat with underlying flap supporting 100 rollers 71 and 72 mounted upon stub axles 73 (Fig. 9). The weight of the rollers 69 and 70 together with the shaft is such that the frame will normally drop down to the position shown in Fig. 5, where the rollers 105 69 and 70 will contact the then outstanding flap and apply paste thereto. Said rollers will have paste imposed upon their surface while they are in their elevated position (Fig. 2) through rollers 74 and 75 mounted 110 upon the constantly driven shaft 54. Said rollers 74 and 75 have paste applied to their surfaces by any suitable means, as for instance, paste reservoirs 76, 77. 115 A latch 78 (Fig. 5) fulcrumed at 79, is employed to hold the frame 66 in such position that the paste rolls 69 and 70 are normally held out of the path of movement of the box flaps, and when so held the belt 60 becomes free and no motion is imparted to 120 the shaft 65. A spring 80 serves to draw the latch toward the frame and the lower end of the latch extends into the runway through which the boxes or cartons are advanced, and contacting the same will throw 125 the latch away from the frame and allow the frame to swing so that the paste applying rolls may come into contact with the then outturned upper flaps, as best indicated in Fig. 5. Mounted upon the horizontally 130

extending bar 21 is an articulated slide 81 (see Fig. 6), said slide at its forward portion carrying a finger 82 which extends into the path of movement of the boxes or cartons and is moved forwardly thereby while the box flaps are passing between the paste applying rolls. The forward member 81^a of the slide is held in its inward position by a spring 83 and the slide as a whole is held in its retracted position by a coil spring 84 attached to the slide at one end and at its opposite end to a fixed portion of the machine. The rear end of the slide is bent or so formed as to be substantially U-shaped, and the forward extending member of the outermost section of the arm or the element indicated by 85 (see Figs. 6 and 10) extends outside of the upright 8 and passes through a guide 86. Said portion of the slide carries an upstanding pin or lug 87 which is in line with an arm or lever 88 secured to and extending downwardly from the shaft 67 upon which the frame 66 is secured. When the box is moved forwardly to such an extent that the flaps clear the paste applying rolls the lug 87 contacts the lower end of the arm 88 and rocks the frame 66 carrying the paste applying rolls upwardly and permitting the latch 78 to engage the rear portion of the frame 66 as the box passes away from or free of such latch. As the box or carton is moved forwardly and comes to the position just noted where the flaps are passing out of contact with the paste applying rolls, the slide 81 is likewise carried forwardly and the forward end 81^a thereof, to which the member 82 is attached, contacts a cam 89 and said forward end is forced or turned inwardly from the position shown in Fig. 6 to that in Fig. 1, whereby the member 82 is carried out of contact with the box or carton and the same is free to move forward in the runway. The cam 89 also acts to prevent the forward hinged end 81^a from being thrown too far inwardly into the runway, and retrograde movement of the slide as a whole beyond a given limit is prevented by a stop 90 extending upwardly from the slide and contacting a guide member 91.

As the box or carton leaves the paste applying rolls the flaps thereof come into contact with two converging flap turning members 92 and 93 arranged in pairs both at the upper and lower portion of the runway. There is also provided at this point and extending inwardly between the flap turning members, a tongue, as 94, there being a tongue at the upper and lower portion of the runway, which tongue is rounded on that face next adjacent the inturning flaps and is tapered toward its outer end where it stops just short of the flap turning elements 92 and 93. By the time the box is advanced through the runway and the flaps begin to leave the tongues, the flaps will have been

turned substantially to their flat position, as indicated in Figs. 4 and 8, and thence pass in between the elements 12 and 13 where the pasted flaps are held in close relation to the underlying flaps 2 and 3. The forward ends 70 of the members 12 and 13 would preferably be cut away to present a V-formation, as best shown in Figs. 6 and 8, and the walls of such cutaway portion are slightly curved or rounded so that the corners or ends of the 75 flaps will ride freely thereover and the flaps forced to their closed position without danger of being torn or otherwise injured or displaced.

Extending longitudinally and centrally 80 of each of the tongues 94 and projecting outwardly therefrom is a flat bar 95 preferably formed of thin steel plate which bar acts to prevent the overlapping of the flaps 4 and 5 and the consequent adhesion of one 85 flap upon the other. While the flaps are ordinarily made of such dimensions that they abut (or approximately so) when completely infolded, it sometimes occurs that the sides of the boxes bulge out and in order 90 to get them back again it is necessary to apply pressure to the boxes. This sometimes causes the flaps to lap one over the other if too much pressure is applied, thereby causing the top flap to be held away from the 95 underlying flaps 2 and 3 by the thickness of itself, thus preventing a bond between the elements. The outstanding bar or element 95, when such condition obtains, throws the flaps upwardly and prevents them from 100 crossing and, as the box is advanced beneath the folding and pressure elements, causes the flaps 4 and 5 to come to their proper position by reason of the outward pressure exerted thereby which carries the sides of the 105 box back to their proper positon.

As before noted the members 12 and 13 may be extended out a considerable length so that the boxes or cartons will be pushed therethrough step by step as each succeeding 110 carton is pushed to place by the advancing chains 18 and 19, or the cartons may be removed and subjected to a heating to dry the paste or stacked up so that the flaps will remain under pressure until the adhesive 115 becomes dry.

While I have described and shown a structure wherein the upper and lower flaps of the box or carton may be sealed, it is evident that if the lower or bottom flaps of the 120 carton are previously sealed prior to filling the box, the machine may, nevertheless, be used for sealing the upper flaps.

The term carton employed in the claims is to be treated as the equivalent of box or 125 the like.

What is claimed is:—

1. In a machine for sealing flaps of cartons, the combination of a runway; means for advancing the cartons therethrough; 130

means for turning oppositely disposed flaps outwardly into substantially horizontal position; means for applying paste to such outturned flaps; means for turning the pasted flaps inwardly over and upon the underlying flaps of the carton; and means acted upon by the box as it is passed through the machine for bringing the paste applying means into and out of operative position.

2. In a machine for sealing the flaps of cartons, the combination of a runway through which the cartons may be passed; means for moving the cartons through such runway; means for turning the pair of the oppositely disposed flaps of the cartons outwardly; paste applying rolls standing in line with such outturned flaps; and means coöperating with the cartons as they are passed through the machine for bringing such rolls into and out of operative position with the flaps of the cartons.

3. In a machine for sealing the flaps of cartons, the combination of a runway; means for advancing the cartons therethrough; means contacting oppositely disposed flaps and turning the same outwardly into a substantially horizontal position; means for applying paste to such outturned flaps; a tongue extending beyond the paste applying means, said tongue narrowing toward its outer end remote from said paste applying means; and means coacting with said tongue to turn the flaps inwardly.

4. In a machine for sealing the flaps of cartons, the combination of a runway; means for advancing the cartons therethrough; means engaging oppositely disposed pairs of flaps and turning them outwardly into substantially horizontal position; paste applying rolls adapted to engage and apply paste to said outturned flaps; a tongue extending from the paste applying means toward the discharge end of the machine, said tongue being rounded upon that face next adjacent the flaps and tapering toward its outer end; and means coöperating with the tongue to turn the flaps inwardly from the tongue and to bring the same to a closed sealed position.

5. In a machine for sealing the flaps of cartons, the combination of a runway; a pair of endless chains having opposite runs thereon coextensive of the runway, means carried by said chains for engaging the cartons and passing them through the runway one by one; a pair of downwardly inclined divergent members contacting the oppositely disposed flaps as the carton enters the machine and acting to turn the flaps outwardly into a substantially horizontal position; paste applying rollers contacting the outturned faces of said flaps; a tongue extending outwardly from the paste apply-

ing means in line with the runway, such tongue narrowing toward the discharge end of the machine; and a pair of flap engaging members, said members converging and engaging the then-under faces of the flaps and turning the same upwardly and over the tongue so that the flaps as the carton is carried through the runway will be turned down into sealing relation.

6. In a machine for sealing the flaps of cartons, the combination of a runway; means for advancing the cartons therethrough; means for turning oppositely disposed flaps of the cartons outwardly into substantially horizontal position; paste applying rolls standing in line with such outturned flaps; a pivoted frame forming the support for said rollers; a latch for normally holding said frame with the rollers elevated out of the path of movement of the flaps; said means standing in the path of movement of the cartons and being released from the frame as the cartons contact said means thereby allowing the roller to drop; means actuated by the forward movement of the carton for elevating the rollers and permitting the frame to become relocked; and means for turning said pasted flaps inwardly into sealing position.

7. In a machine for sealing the flaps of cartons, the combination of a runway; means for advancing cartons therethrough; means acting upon the inner edges of the flaps to force the same bodily outwardly to bring them to a position where they will not overlap; and means for forcing the flaps into sealing contact with the underlying portions of the carton.

8. In a machine for sealing cartons having flaps, the combination of a runway; means for advancing the cartons therethrough; means for turning the flaps inwardly into adhesive relation with the underlying portions of the carton; and means acting upon the proximate edges of the flaps to prevent the same from overlapping as they are turned inwardly into sealing relation.

9. In a machine for sealing cartons having flaps, the combination of a runway; means for advancing the cartons therethrough; means for turning opposite flaps inwardly into sealing position; and means coöperating with said inturned means to prevent the flaps overlapping as they are turned inwardly into sealing position.

10. In a machine for sealing cartons having flaps, the combination of a runway; means for advancing cartons therethrough; and an upstanding bar located in line with the inner adjacent edges of the flaps and acting to prevent overlapping of the same as the flaps are turned inwardly into sealing contact with the underlying portions of the carton.

11. In a machine for sealing cartons having flaps, the combination of a runway; means for advancing the cartons therethrough; means for turning opposite flaps outwardly to a substantially horizontal position; means for applying paste to the outwarded flaps while in such position; means for thereafter turning the flaps inwardly to bring them into sealing contact with the other box flaps; and means coacting with the inner edges of the flaps to prevent the same from overlapping as they are turned inwardly into sealing position. 20
12. In a machine for sealing cartons having flaps, the combination of a runway; means for advancing the cartons therethrough; means for applying paste to the carton elements which are to be brought into adhesive relation; means for turning opposite flaps inwardly; a tongue lying in the runway beneath the path of the flaps to be inturned; and an upstanding bar carried by the tongue and preventing overlapping of the proximate edges of the flaps which are being inturned. 25
13. In a machine for sealing cartons having flaps; means for turning the flaps inwardly into sealing position; and means associated therewith to force the flaps bodily outwardly away from each other to prevent overlapping of the proximate edges thereof when they are brought to their final sealed position. 30

In testimony whereof I have signed my name to this specification.

JOHN A. MOORE.
